UNITED STATES PATENT OFFICE

CLARENCE L. PATTERSON, OF CINCINNATI, OHIO, ASSIGNOR TO THE INTERNATIONAL MANUFACTURING COMPANY, OF CINCINNATI, OHIO, A CORPORATION OF OHIO

LAMP CONTROL DEVICE

Application filed April 14, 1930, Serial No. 444,103. Renewed April 23, 1932.

An object of my invention is to produce a device whereby redirection or control of the rays of light projected from an automobile lamp for purposes of preventing the glare or blinding beam of light which meets the driver of an approaching vehicle, is accomplished in an unique manner radically different from established custom, in that the use of two filament bulbs and special circuits, resistances and the like is rendered unnecessary.

A further object is to produce such a device as will cause redirection of light rays without having to resort to the alternate illumination of separate bulb filaments for such a purpose.

These and other objects are attained in the lamp control device now to be described.

In the drawing, Fig. 1 is a somewhat diagrammatic view embodying a form of my invention, the reflector and other parts being shown in section for clearness of illustration.

Fig. 2 is an enlarged perspective view showing an important element of my invention with a part broken away for purposes of illustration.

Fig. 3 is a diagrammatic view showing a circuit incorporating the invention I will now describe.

Fig. 4 is a modification of my invention.

I have shown a reflector 6, which is shown fragmentally and in section, equipped with a central opening in which is clinched a collar 7 adapted to mount a connector tube 8 in a manner to be explained. This connector mounts a lamp bulb 9 in the usual manner, so that its filament will be located for position in the focal zone of the reflector as shown in full lines in Fig. 1. Reflector collar 7 is provided with ears 10 which may have a bayonet slot 11 in each, to mount a pivot pin 12 on each side of the connector in order that the connector may be moved pivotally thereon within the opening of collar 7. Lug 13 on the collar limits the downward movement of bulb 9 to a position in which the filament 15 is located in the focal zone of the reflector, and collar lug 14 is provided for limiting the tilting movement of the connector so that the bulb filament will not be permitted to

pass beyond the dotted line position shown in Fig. 1. In the full line position of the bulb, filament, connector, and associated parts, the beam projected by the lamp reflector takes the direction indicated by the forwardly projecting substantially parallel full lines 16 and 17 which represent typical rays of such a beam. In the dotted line position of the bulb, the beam projected takes the direction indicated by the spreading and downwardly inclined dotted lines 18 and 19 which represent typical rays of such a beam.

To accomplish this tilting movement of the bulb, I have provided a finger 20 extending to the rear of the connector, which is connected by a rivet or other suitable connection, with the rear end of a thermostatic device 21, the opposite end of this device being similarly connected with a lug 22 extending from reflector collar 7. This thermostatic device is of simple construction and consists merely in laminations 23 and 24 of different metals which may be either basic or are alloys. The characteristics of these metals are such that the metal of lamina 23 will expand, when subjected to heat, relatively rapidly as compared to the rate of expansion of the metal of lamina 24. The result of this reaction to heat is to cause the lamina 23 to lengthen much more rapidly than does lamina 24. Thus, when the ends are held together as shown in Fig. 1, there will occur a straightening movement tending to cause it to assume some such slope as shown in dotted lines. This, therefore, causes the tilting of the bulb, as shown, so that the filament is moved from the full line position to the dotted line position shown, thus causing a change in beam from the full line beam, disclosed at 16 and 17, to the dotted line beam shown at 18 and 19.

Now, all that remains is to provide a convenient means by which the thermostatic element may be heated. This is readily accomplished by merely passing an electric current directly through the metal of the thermostat, provided such material is of correct resistance to produce the desired heating effect, or by means of a layer or coil of resistance wire 25 which, in the illustrated embodiment, is superposed on lamina 23. I hold this layer

of wire in position preferably by means of a covering of mica or other insulating material 26, thereby also protecting the resistance wire against possible damage,

5 If this wire is connected in a suitable circuit designed to permit control of the lamp, both as to illumination and tilting of the bulb, the proper functioning of the device may be controlled. Such a circuit is illustrated diagrammatically and by way of example, in Fig. 3, which I will now describe. In this view I have shown the usual storage battery 27 as the source of energy, as well as two lamp bulbs 28 and 29, which are to 10 be controlled. A switch 30, which will be described, is provided for controlling the illumination of the lamp filaments and the functioning of the thermostatic devices 31 and 32. In the type of lamp bulbs illustrated diagrammatically, each has two filaments 33 and 34, 33 being a relatively high candle power filament and 34 a low candle power filament. The filament 34 of each bulb, is employed only when the vehicle is standing still and 15 does not enter directly into the invention herein set forth, but, nevertheless, is disclosed for purposes of showing the adaptability of my invention to bulb equipment of this type. In the embodied circuit connections of Fig. 3, I have disclosed switch 30 as a three contact switch, merely for purposes of illustration, it being understood that I may as readily employ separate switches in lieu thereof, or that I may arrange for 20 partial foot or hand control of such switches, or that the operation of such switches may be made entirely by hand or entirely by foot. I have shown a system of connections in which one pole of the battery is grounded to 25 the frame of the vehicle and in which one terminal of each of the filaments is also grounded, thus providing the return circuit connections. From the opposite pole of the battery I provide a connection 35 to the common terminal 36 of the switch. The remaining terminals 37, 38 and 39 are connected with the filaments 33 and 34 as follows. First, I will dispose of the connection with filament 34 of each lamp. This is merely accomplished by a wire 40 which is branched to connect terminal 37 of the switch with one terminal of each of the filaments 34, as shown, the opposite terminal of each filament 34 being connected with the ground by a wire 45 41. Terminal 38 of switch 30 is connected with one terminal of each of the thermostatic control devices 31 and 32 by a branched wire 42, the opposite terminal of each of the devices 31 and 32 being connected with the main filament 33 of each bulb by a wire 43 to place it in series with the filament, or, if preferred, it may be placed in parallel connection with the filament as shown in the modification disclosed in Fig. 4. Finally, in 50 55 60 65 65 order that switch connection 39 may be placed

in the circuit in the manner intended, a branched wire 44 is led to and connected directly with the ungrounded terminal of each filament 33.

The operation of my improved device is accomplished, in the illustrated embodiment, by mere operation of switch 30. For example, when the switch closes the circuit through contact 37, the filaments 34 are caused to glow for illumination while the vehicle is parked. When driving in cities, in localities where considerable traffic exists, or in passing a vehicle when traveling at night along country roads, it is desirable that the head lamp illumination be somewhat diffused and less penetrating so that the blinding glare which often is experienced in passing motor vehicles is completely avoided without in any manner operating to diminish the intensity of the light. This is accomplished by operating switch 30 to close the circuit through contact 38. Thus, the current passes through wire 42, through thermostatic devices 31 and 32, through filaments 33, and through the "ground" back to the battery. The effect of this is to illuminate filaments 33 with full brilliancy and, simultaneously therewith, to cause devices 31 and 32 to become hot and thereby cause the thermostat 21 of each head lamp to affect a tilting of each bulb from a position such as shown in full lines in Fig. 1, to a position such as shown in dotted lines. This is caused by a relative expansion of the metals 23 and 24 of each thermostat. Should it be that the parallel connection of thermostatic devices and bulb filament, as shown in Fig. 4, be embodied in lieu of the series connection shown in Fig. 1, the operation of thermostat and filament will be the same, and the diffused light thus resulting will be of full brilliancy with illumination of the roadway and without the blinding brilliancy of illumination which characterizes a beam of light projected from a filament located in the focal zone of the reflector. When the vehicle driver has reached a clear and open stretch of roadway, he needs a beam of light of high power and which will operate to pierce the darkness at a great distance from the car. This is produced by moving the switch to close the circuit between contacts 36 and 39. In this manner the thermostatic devices are disconnected and the circuit is established directly through branched wire 44, through wires 43, and through filaments 33 to the return circuit through the "ground". In such a condition the thermostatic devices, being cool, maintain the bulb filaments directly in the focal zone, as shown in Fig. 1, thus producing the straight-ahead beam shown in full lines in Fig. 1.

It is obvious that many modifications may be made in the form of thermostatic device employed, and that it may be variously connected with the lamp bulb, connector, re-

5 reflector, or lamp body, and that, furthermore, the movement of these parts may be accomplished pivotally or otherwise, as best befits the preference of the designer, without departing from the spirit and scope of my invention as set forth in the appended claims.

10 Although I have described my invention as having been applied, by way of example, to the lamp bulb directly, it is obvious that it may as readily be applied to the reflector in order to move it instead of the bulb, or that it may as readily be employed to move the reflector and bulb as a unit in order to bring about a redirection of the beam of light. Developing 15 this thought of moving the reflector and bulb as a unit, it is obvious that the same function may be accomplished by connecting the thermostat and its operating circuit with a lamp which, in its entirety, is pivotally mounted for and capable of producing the results which have been described.

Having thus described my invention, what I claim is:

20 1. A lamp control device comprising in combination with a lamp containing a reflector, and a lamp bulb therein movable to positions into or out of the focal zone of the reflector, a thermostat mounted on a relatively fixed element of the lamp and connected with the bulb, adapted when heated to move the bulb from one of its positions to the other, and means controlling the application of heat to the thermostat, adapted to cause the bulb to be moved when desired.

25 2. A lamp control device comprising in combination with a lamp containing a reflector, and a lamp bulb movable therein to bring its filament into or out of the focal zone of the reflector, a thermostat mounted on a relatively fixed element of the lamp, and connected with the bulb, adapted when heated to move the bulb from one of its positions to the other, an electric heater adapted to function the thermostat, and a controllable circuit to control the heater.

30 3. A lamp control device comprising in combination with a lamp containing a reflector and a lamp bulb pivotally mounted therein for movement from a position in which its filament occupies the focal zone of the reflector, to a position out of the focal zone, a thermostat consisting of a structure of laminated materials having different rates of expansion under heat, said thermostat being mounted on a relatively fixed element of the lamp and connected with the bulb to move it when it is heated, an electric heater to heat the thermostat, a circuit connecting the heater and the filament of the bulb, and means to control the circuit to function the filament individually or the filament and heater jointly.

35 In testimony whereof I hereunto affix my signature.

CLARENCE L. PATTERSON.
